UNITED STATES PATENT OFFICE.

FREDERICK WILL AND HUGO BECKER, OF ROCHESTER, NEW YORK, ASSIGNEES TO
SILL STOVE WORKS, OF ROCHESTER, NEW YORK, A CORPORATION OF NEW YORK.

GAS-STOVE.

1,089,172.

Specification of Letters Patent. Patented Mar. 3, 1914.

Application filed January 22, 1912. Serial No. 672,623.

To all whom it may concern:

Be it known that we, FREDERICK WILL and HUGO BECKER, both of Rochester, in the county of Monroe and State of New York, have invented certain new and useful Improvements in Gas-Stoves; and we do hereby declare the following to be a full, clear, and exact description of the same, reference being had to the accompanying drawings, forming a part of this specification, and to the reference-numerals marked thereon.

Our present invention relates to improvements in gas stoves, and more particularly to the type of stove employed both for baking and broiling, and it has for its object to provide means for enabling the stove to be used more readily for broiling.

A further object of the invention is the provision of a construction whereby when the gas stove is used for broiling purposes, the broiler is in a convenient position and more readily accessible to the operator.

Another object of the invention is to provide a structure that enables the bottom of the gas stove to serve as a supporting means for the broiler, when the latter is to be used.

Still a further object of the invention resides in the provision of means for increasing the heating capacity of the burners under the oven.

To these and other ends the invention consists in certain improvements and combinations of parts all as will be hereinafter more fully described, the novel features being pointed out in the claims at the end of the specification.

In the drawings: Figure 1 is a view in front elevation showing the upper portion of a coal range and a gas stove arranged thereabove, embodying a preferred form of the invention; Fig. 2 is a sectional view on the line $x-x$ of Fig. 1; Fig. 3 is a sectional view on the line $y-y$ of Fig. 2, taken in the direction of the arrows and showing in dotted lines the position of the sections of the stove bottom when the broiler is in use; Fig. 4 is a sectional view on the line $a-a$ of Fig. 2, looking downwardly; Fig. 5 is an enlarged sectional view on the line $b-b$ of Fig. 3, taken in the direction of the arrows, and Fig. 6 is an enlarged sectional view on the line $c-c$ of Fig. 4, in the direction indicated.

Similar reference numerals throughout the several figures indicate the same parts.

The invention is susceptible of a number

of different applications, and we have shown a preferred form as embodied in a combination stove, including a coal range and a gas stove arranged thereabove, the upper part of the coal range being designated at 1, while 20 2 is the main flue connected, as shown, with the coal range, and connected by the pipe 3 with the gas stove, the latter being arranged above the top of the coal range. The passage 3 from the gas stove is preferably controlled by the damper 4 which is connected to a lever 5, the latter having an enlargement 6 at its forward end arranged to be engaged by the door 7 for closing the gas oven 8. By this means, whenever the gas 70 oven is opened, the damper 4 is also opened, to insure the passing of the products and gases to the flue, and to prevent their entering the room.

Burners 9 are suitably arranged below the 75 gas oven, between said oven and the stove bottom, as usual in this type of stove. Heretofore, it has been necessary to provide a separate compartment or sections in the gas stove including additional burners to be used 80 for broiling, and it is one of the purposes of the present improvement to enable the same burners to be used for heating the gas oven and for broiling. To this end, in the present embodiment, the bottom of the gas stove is 85 constructed so as to be moved away from the burners and to enable the broiler to be placed in the proper cooking relation. This is accomplished by forming a movable section in the stove bottom, the latter preferably including a pair of sections 10 provided with suitable trunnions 11 which are supported in the bearings 12. The sections 10 are held in their normal or raised positions by means of a pivotally mounted latch 13, 90 and when released, assume the positions shown in dotted lines in Fig. 3, the projections 14 serving as stops to limit their movement, and fix the position of the sections when lowered. The sections 10 are provided 95 with a series of guideways, preferably formed by means of the several sets of lugs 15, as shown, and when the sections are lowered the broiler 16 may be supported in the position shown in Fig. 3, or in any of the 100 other guideways according to the degree of heat required for the article to be cooked. Lugs 17 are provided on the stove for supporting the broiler conveniently when the sections 10 are raised.

When the parts are in normal position as shown in full lines in Fig. 3, the gas oven may be used in the usual manner. When broiling is to be done, the broiler is removed, 5 the sections 10 being released and dropped downwardly, whereupon the broiler may be inserted at the desired elevation, and the broiling operation proceeded with. By this arrangement, a very convenient and compact construction is provided, accomplishing 10 all the purposes that have heretofore required a much larger form of stove. Further, the broiler is brought nearer to the top of the coal range, thus making it more accessible and enabling the article being cooked 15 to be watched and controlled with greater facility. The space above the coal range, that is saved by the present arrangement may be employed for any convenient purpose, and in the present embodiment, is utilized by a shelf 18.

The lugs 15 on the stove bottom serve, also, to hold the heat from the burners and to supply it to the oven for a longer period 25 after the burners are shut off.

While we have described the invention with reference to a particular embodiment, its application is not limited to the exact construction disclosed, since it comprehends 30 any modification coming within the terms of the claims hereinafter.

What we claim is:

1. A gas stove comprising a burner, a stove bottom disposed below the burner, 35 said stove bottom including a pair of hinged sections and means for supporting a broiler below the burner when the sections are lowered.

2. A gas stove comprising a burner, a 40 stove bottom disposed below the burner, said stove bottom including a pair of movable sections adapted to be lowered from their normal position, and means carried by the sections for supporting a broiler between 45 them when the sections are lowered.

3. A gas stove comprising a burner, a stove bottom disposed below the burner, said stove bottom including a pair of hinged sections, and guideways arranged on the sections whereby to support a broiler when the 50 sections are lowered.

4. A gas stove comprising a burner, a stove bottom disposed below the burner, said stove bottom including a pair of hinged sections, guideways arranged on the sections 55 whereby to support a broiler when the sections are lowered, and means for holding the sections raised.

5. A gas stove comprising a burner, a stove bottom disposed below the burner, said 60 stove bottom including hinged sections movable to a vertical position, and means carried by said sections for supporting a broiler below the burner when in such vertical position.

6. A gas stove comprising a burner, a stove bottom disposed below the burner, and movable to a vertical position, said movable bottom including means for supporting a broiler below the burner when in said vertical position.

7. A gas stove comprising a burner, and a hinged stove bottom disposed below the burner and adapted to be lowered from its normal position, said hinged bottom includ- 75 ing means for supporting a broiler in various positions below the burner when the bottom is lowered.

8. A gas stove comprising a burner, broiler supporting sections which are mov- 80 able and adapted to be lowered to vertical positions beneath the burner, and means carried by the sections for supporting a broiler therebetween when the sections are lowered.

FREDERICK WILL.
HUGO BECKER.
